 Detroit Lubricator Company, Detroit, Mich., a
 corporation of Michigan

Application July 9, 1945, Serial No. 603,945

17 Claims. (Cl. 137—68)

1

This invention relates to new and useful improvements in devices for controlling the flow of liquid fuel to gravity fed oil burners.

In operating gravity fed oil burners, it is desirable to be able to control the fuel flow not only for high fire burner operation, but also for pilot operation at extremely low flow rates. When the fuel flow is decreased to a rate of one c.c. per minute, the orifice is so small that it quickly clogs with foreign matter, such as gum or wax, carried in the oil. However, such a small flow rate provides an ample pilot flame, but it can not be maintained unless the orifice is kept clean and foreign matter is cleared away from the orifice.

It is accordingly one object of this invention to provide means for cleaning the pilot orifice.

Another object is to provide means to wash away orifice obstructing matter by utilizing liquid fuel under higher pressure than the normal head pressure on the orifice.

The invention consists in the novel construction and combination of parts to be more fully described hereinafter, and the novelty of which will be particularly pointed out and distinctly claimed.

In the accompanying drawings, to be taken as a part of this specification, there are fully and clearly illustrated various preferred embodiments of the invention, in which drawings,

Figure 1 is a diagrammatic view of a liquid fuel burning system having the fuel flow controlling device shown in vertical section,

Fig. 2 is an enlarged detail view taken on the line 2—2 of Fig. 1 and showing the pilot fire metering orifice,

Fig. 3 is a view partly in vertical section showing another form of fuel outlet controlling means,

Fig. 4 is a diagrammatic view of a liquid fuel burning system having another form of fuel flow controlling device shown in vertical section,

Fig. 5 is a detail view in section on the line 5—5 of Fig. 4, and

Fig. 6 is a view partly in vertical section showing still another form of fuel outlet controlling means.

Referring to the drawings by characters of reference, and first to Figures 1 and 2, the numeral 1 designates a liquid level chamber or casing having a bottom wall 2 with an inlet connection 3 having an inlet passageway 4 which receives liquid fuel such as fuel oil, under pressure from a pipe 5 screwed into the connection 3. The pipe 5 leads to the outlet from an elevated fuel supply tank 6. Flow of fuel from the tank 6 is controlled by a shut off valve 7 in the pipe 5.

2

Screw threaded into the connection 3 there is a valve casing 8 having an inlet port 9 communicating with the passageway 4 and opening into a valve chamber 10. In the chamber 10 there is a valve member 11 which is longitudinally reciprocal to open and close the port 9. The valve member 11 has a stem 12 which extends upward through and has a sliding fit in a guide member 13 on the casing 8, the stem extending into the chamber 1. The valve casing outlet 14 has a conduit or duct 15 connected thereto. The valve member 11 is opened and closed by a hollow metal float 16 of annular form and having a lever arm 17 with its free end positioned between the flanges of a collar 18 fixed on the upper end of the stem 12. The lever 17 is pivotally supported on a shaft 19 extending between and carried by the walls of the casing 1. Concentric with the float 16 and extending upward into the chamber 10 from the bottom wall 2 there is a tubular outlet member 20 having a vertical passageway 21 therethrough and opening into an outlet connection 22. Slidably fitting in the tubular member 20 there is a tubular or cylindrical valve member 23 having a metering slot 24 cooperable with a surrounding cut-off shoulder 25 formed by an enlargement of the passageway 21. This enlargement also forms at the upper end of the passageway 21 a valve seat 26 below the liquid level in the chamber 1. The valve member 23 also has a fuel flow restricting orifice 27 opposite the slot 24 and of V or triangular shape, see Fig. 2. The orifice 27 which provides fuel flow for pilot fire to the outlet connection 22 is registerable with an aperture 28 through the side wall of the conduit member 20. The aperture 28 receives the free end of the tube or conduit 15 which has a port 29 below the liquid level in the chamber 1 and adjacent the tubular member 20 such that the port 29, aperture 28 and the portion of the conduit 15 therebetween provide an outlet conduit from the chamber 1 to the orifice 27. The float 16 carries an armature 30 cooperable with a permanent magnet 31 carried by a bracket 32 secured to the side wall of the casing 1. The magnet acts on the armature 30 tending to move the valve member 11 to its seat to close the port 9 and when the liquid level in the chamber 1 rises to the line L the magnet 31 will lift the float slightly and tightly close the valve member 11. The magnet 31 will hold the float 16 in elevated position and the valve member 11 tightly closed until the fuel flow from the chamber 1 through the port 29, conduit 15 and orifice 27 decreases the liquid level 55 sufficiently so that the weight of the float 16

overcomes the force of the magnet 31. This lower liquid level may be such as indicated by the line L₁ and when the float 16 drops to its normal floating depth at this new level L₁, the valve member 11 will be lifted to wide open position. In its wide open position the valve member 11 will be positioned for fuel flow through the inlet 9 at a rate in excess of the combined flow rates through the port 29 and the orifice 27. Therefore when the valve member 11 is opened the fuel oil under the high head pressure from the elevated tank 6 will rush through the conduit 15 for discharge under pressure through the orifice 27 into the outlet passageway 21 and through the port 29 into the chamber 1. This rush of oil through the orifice 27 will clean the orifice of any accumulated wax or other orifice obstructing material. Due to the high rate of inflow of oil into the chamber 1 through the port 29, the liquid level will be quickly raised to the line L, whereupon the valve member 11 will be closed by the action of the float 16 and magnet 31. After this short interval of orifice cleaning, the predetermined minimum flow for pilot fire operation will continue from the chamber 1 through outlet conduit 29, 15 and 28 to and through the metering orifice 27.

Cooperable with the seat 26 to close the inlet port to the slot 24 there is a sleeve valve 33 which slidably fits the valve member 23, extending upward therewith through the central aperture in the float 16. The sleeve valve 33 is connected to the valve member 23 by a lost-motion pin and slot engagement 34 such that the sleeve valve 33 is held to its seat 26 by the lost-motion spring 35 until the orifice 27 is moved upward out of registry with the aperture 28. The spring 35 abuts a flange 36 on the valve member 23 and when the lost-motion connection 34 is taken up then the spring 37 which is under compression between the outlet member 20 and the sleeve valve 33, will move the sleeve valve and the valve member 23 upward. Upward movement of the sleeve valve 33 will open the port in the upper end of the outlet member 20 for flow from the chamber 1 to and through the metering slot 24 to the outlet connection 22. The size of the orifice 27 is determined by the screw stop member 38 cooperable with the flange 36 to limit downward movement of the tubular valve member 23. A guide member 39 cooperates with an aperture through the flange 36 to hold the orifice 27 in vertical alignment with the aperture 28 and prevents rotation of the valve member 23. The maximum opening movement or upward movement of the tubular valve member 23 for high fire flow through slot 24 is determined by a high fire stop screw 40 engageable with the top face of the flange 36.

The outlet valve member 23 may be manually controlled but is here shown as movable by a thermostatic power element 41 having a bulb element 42 responsive to the temperature of a medium to be heated such as liquid contained in the heating space 43 of a heating apparatus 44 having a burner pot 45. The outlet connection 22 receives a fuel pipe 46 which leads to the pot 45 which is preferably of the vaporizing type having air inlet apertures 47 supplied with combustion supporting air from an air supply duct 48.

The operation of this system is as follows: With the metering slot 24 and sleeve valve 33 closed as shown due to the bulb element 42 having been heated to the desired temperature, the float 16 and magnet 31 will act to alternately and intermittently move the inlet valve member 11 to full

closed and wide open positions. Each time that the liquid level drops to the line L₁, the valve member 11 will be quickly moved to wide open position to admit fuel under pressure to the conduit 15 to flush and clean the orifice 27 so that the desired extremely low rate of fuel flow for a minimum pilot flame will be maintained during the intervals when the valve member 11 is closed. It will be apparent that the time interval between successive discharges of fuel under pressure from the tank 6 through the orifice 27 will be determined by the size of the orifice 27, the viscosity of the oil, the head pressure of the oil in the chamber 1 on the orifice 27 and the volume of the oil between the levels L and L₁. The length of the flushing interval is determined by the rate of flow from tank 6 through port 29 into the chamber 1 which will raise the level from L₁ to L. When a high burner flame is desired, as results when the temperature of the bulb element 42 decreases to the desired low limit, the lost-motion spring 35 will move the valve member 23 upward thereby closing the pilot orifice 27 while holding the sleeve valve to its seat 26. When the lost-motion connection 34 is taken up by the spring 35 then the spring 37 will lift the sleeve valve 33 and since the slot 24 is open for fuel flow, fuel will flow from the chamber 1 across the shoulder 25 and through the slot 24 to the burner pot 45. The spring 37 will continue the opening movement of the slot 24 until the flange 36 engages the high fire stop screw 40. Fuel will now be fed to the chamber 1 from the tank 6 through the port 29 as above described but with more rapid alternations of the opening and closing of the valve member 11 due to the greater rate of outflow through the slot 24.

Referring to Fig. 3, the parts are as above described except for the outlet controlling valve member. In this form the valve member 50 is of one piece construction having a pilot orifice 51 of fixed size and having the shut-off valve portion 52, corresponding to the sleeve valve 33, rigid with the portion of the valve member 50 which contains the metering slot 24. The orifice 51 is moved into registry with the outlet member side wall aperture 28 when the slot 24 is closed by the cut-off shoulder 25. The valve portion 52 closes off flow to the shoulder 25 when the orifice 51 is in registry with the aperture 28. The operation of the construction of this Fig. 3 will be apparent from the above description of operation of Fig. 1.

Referring to Figs. 4 and 5, the elevated liquid fuel supply tank 60 containing fuel oil is connected by an outlet pipe 61 to the inlet connection 62 of liquid fuel chamber or casing 63. A shut-off valve 64 is preferably provided in the pipe 61. Screw threaded into the connection 62 within the chamber 63 there is a valve casing 65 having an inlet port 66 leading to a valve chamber 67 having an outlet port 68. The inlet port 66 is controlled by a valve member 69 longitudinally reciprocal in the chamber 67 and operable to open and close the port 66. The valve member 69 has a stem 70 which extends upward into the chamber 63 through a guide member 71 on the casing 65. The valve member 69 is moved to open and closed positions by a float 72 responsive to liquid level in the chamber 63. The float 72 has a lever arm 73 which extends at its free end between a collar 74 secured on the upper end of the stem 70. The lever arm 73 is journaled on a shaft 75 secured to the wall of the casing 63. The float 72 carries an armature 76 cooperable with a magnet 77 carried by a bracket 78 pro-

jecting inward from the side wall casing 63. The magnet 77 and its armature 76 cooperate with the float 72 as above described in connection with Fig. 1 to close the valve member 69 when the liquid level reaches the line L and to open the valve port 66 when the liquid level drops to the line L₁. The float 72 is of annular form and extending upward through its central aperture there is an outlet controlling valve member 79 of tubular or cylindrical form. The valve member 79 has adjacent its lower end portion 80 which is of reduced external diameter, a conical cut-off or valve portion 81. The lower portion 80 reciprocally fits the outlet passage 82 of a tubular outlet number 83. The member 83 extends upward into the chamber 63 terminating below the lower liquid level L₁ and has its upper passageway portion of enlarged diameter as at 84 to provide an annular flow space around the valve member portion 83. At its lower end the space 84 provides a cut-off shoulder 85 cooperable with a longitudinal slot 86 in the lower valve portion 80. The upper end of the tubular member 83 around the enlarged portion provides a valve seat for engagement by the conical valve portion 81. The enlarged portion 84 also provides an outlet conduit leading to the metering orifice or slot 88 and with its upper inlet end portion providing a port for flow from the space 84 into the chamber 63. Through the side wall of the tubular member 83 there is an aperture 87, see Fig. 5, opening into the outlet conduit 84 between its inlet port and the metering orifice. Directly connecting the outlet port 88 of the valve casing 65 and the aperture 87 there is a tube or conduit 89 for conveying liquid fuel under pressure from the tank 60 to the metering slot 88 and to the chamber 63. The side wall aperture 87 enters the space 84 tangentially and is circumferentially spaced from the orifice 88 so that the liquid fuel entering the outlet conduit 84 from the conduit 89 will not be discharged directly through the outlet orifice 88 and will sweep around the valve portion 80 to clear the orifice of foreign matter. The valve member 79 is held against rotation by a cross pin 90 vertically reciprocal in a slot or member 91 extending downward into the casing 63 from its cover member 91. The valve member 79 is moved to open position by a spring 92 which holds the valve member against an adjustment screw 93 carried by the cover member 91. Adjustment of the screw 93 will control the size of the orifice through the slot 86 above the shoulder 85. The outlet passage 82 opens into an outlet connection 94 which is connected by a pipe 95 to the burner pot 96 of a vaporizing type of liquid fuel burner such as described in connection with Fig. 1.

The operation of this control device and system of Fig. 4 it is believed will be apparent from the foregoing description of Fig. 1. However, it may be noted, that the space 84 provides sufficient restriction to flow into the chamber 63 when the valve member 69 is in wide open position so that the inrush of fuel through the conduit 89 will be in part discharged through the slot 86 when it is in minimum open position for pilot fire operation of the burner.

Referring to Figure 6, the outlet control valve is substantially the same as that shown in Fig. 4. In this form of Fig. 6 the tubular outlet member 83 has a valve seat 100 surrounding and concentric with the valve seat 101 engaged by the conical valve portion 81. Surrounding the valve member 79 there is a cylindrical sleeve 102 which

5 seats on the valve seat 100 and which has a lost-motion connection with the valve member 79 as at 103. In the lower edge of the sleeve 102 there is a port 104 which restricts flow from the conduit 89 into the liquid fuel chamber.

10 The effective flow area of the metering slot 86 when the sleeve 102 is seated and of the port 104 is less than the effective flow area of the valve member 69 when in wide open position so that the liquid fuel in the outlet conduit or flow space 84 is under a higher pressure than the pressure on the orifice 88 due to the head of oil in the liquid fuel chamber when the valve member 69 is closed. It may be noted that the slot 86 is moved to closed position before the valve portion 81 engages its seat 101. Also the effective flow area of the inlet port around the valve portion 81 to the conduit 84 when the slot 86 is just closed is greater than the effective flow area of the port 104. The size of the port 104 will determine the head pressure on the orifice 88 when the valve member 69 is in wide open position and will also determine the quantity of excess fuel discharged through the orifice 88 by determining the duration of the open position of the valve member 69. The operation of this outlet valve will otherwise be apparent from the foregoing description.

30 What is claimed and is desired to be secured by Letters Patent of the United States is:

1. Fuel feeding means comprising a casing having a liquid fuel chamber and having an outlet, means for conducting fuel from said chamber to said outlet and having a submerged outlet orifice controlling the discharge of fuel under the chamber head pressure to said outlet, and means to discharge fuel through said orifice to said outlet under a higher head pressure than the chamber head pressure on said orifice thereby to wash orifice obstructing matter through said orifice.

35 2. Fuel feeding means comprising a casing having a liquid fuel chamber and having an outlet, means for conducting fuel from said chamber to said outlet and having a submerged outlet orifice controlling the discharge of fuel under the chamber head pressure to said outlet, a conduit to discharge fuel through said orifice to said outlet under a higher head pressure than the chamber head pressure on said orifice thereby to wash orifice obstructing matter through said orifice, and means to intermittently permit and shut off flow of fuel thru said conduit.

40 3. Fuel feeding means comprising a casing having a liquid fuel chamber, a liquid fuel supply conduit having an inlet external of said chamber and having a port and an orifice for simultaneous discharge from said conduit, said port discharging into said chamber, said orifice discharging external of said chamber, and a valve in said conduit controlling flow from said inlet simultaneously to and through both said port and said orifice.

45 4. Fuel feeding means comprising a casing having a liquid fuel chamber, a liquid fuel supply conduit having an inlet external of said chamber and having a port and an orifice for simultaneous discharge from said conduit, said port discharging into said chamber, said orifice discharging external of said chamber, a valve in said conduit controlling flow from said inlet simultaneously to and through both said port and said orifice, and means intermittently acting to open and close said valve.

50 5. Fuel feeding means comprising a casing having a liquid fuel chamber, a liquid fuel supply con-

duit having an inlet external of said chamber and having a port and an orifice for simultaneous discharge from said conduit, said port discharging into said chamber, said orifice discharging external of said chamber, a valve in said conduit controlling flow from said inlet simultaneously to and through both said port and said orifice, and means in said chamber and controlling said valve and including a float and a magnet co-operable with said float, said means intermittently acting to open and close said valve upon change of chamber liquid level.

6. Fuel feeding means comprising a casing having a liquid fuel chamber, a liquid fuel supply conduit having an inlet external of said chamber and having a port and an orifice for simultaneous discharge from said conduit, said port discharging into said chamber, said orifice discharging external of said chamber, a valve in said conduit controlling flow from said inlet simultaneously to and through both said port and said orifice, and means to close said orifice irrespective of the position of said valve.

7. Fuel feeding means for supplying fuel to a liquid fuel burner, comprising a casing having a liquid fuel chamber and having an outlet conduit with an inlet port below the chamber liquid level, said conduit having a metering orifice for pilot flame burner operation and supplied by said port, a fuel supply conduit connected into said outlet conduit between said port and said orifice, a valve controlling admission of fuel to said supply conduit, and means to open said valve to a position for a greater rate of flow to said supply conduit than the combined rates of flow from said supply conduit through said inlet port and through said orifice so that fuel under pressure will be discharged through said orifice to wash away orifice obstructing matter.

8. Fuel feeding means for supplying fuel to a liquid fuel burner, comprising a casing having a liquid fuel chamber and having an outlet conduit with an inlet port below the chamber liquid level, flow restricting means in said conduit determining the flow for pilot flame burner operation, a valve casing having an inlet and an outlet, a valve member controlling flow through said casing, means including means responsive to liquid level in said chamber and operable alternately to open and close said valve member, and a supply conduit leading from said valve casing outlet and connected into said outlet conduit between said inlet port and said restricting means, said port restricting flow from said supply conduit to said chamber thereby to increase the flow through said restricting means when said valve member is open.

9. Fuel feeding means comprising a casing having a liquid fuel chamber and having an outlet orifice, valve means controlling admission of liquid fuel to said chamber, means operable by change of liquid level in said chamber and controlling said valve means, magnetic means determining the extent of change of liquid level for operation of said valve means by said liquid level means, and conduit means leading directly to said orifice from said valve means to discharge fuel through said orifice thereby to wash orifice obstructing matter away from said orifice.

10. Fuel feeding means comprising a casing having a liquid fuel chamber and having an outlet conduit with an outlet orifice, valve means controlling admission of liquid fuel to said chamber, metering means connecting said chamber to said outlet conduit in by-passing relation to said

orifice, and conduit means leading directly to said orifice from said valve means thereby to wash orifice obstructing matter away from said orifice.

11. Liquid fuel feeding means comprising a casing having a liquid fuel chamber, a tubular outlet member extending upward in said chamber, a metering member reciprocal in said outlet member and having a metering orifice, said outlet member having a side wall opening for flow to said orifice, valve means having an inlet for liquid fuel and an outlet, and a conduit connecting said valve means outlet to said side wall opening so that upon opening of said valve means liquid fuel will be supplied to said orifice to wash away orifice obstructing matter.

12. Liquid fuel feeding means for supplying fuel to a liquid fuel burner, comprising a casing having a liquid fuel chamber and having an outlet, means providing a metering orifice below the liquid level in said chamber and discharging into said outlet, a valve casing having an inlet and an outlet and carried by said chamber, a conduit connecting said valve casing outlet to the inlet side of said orifice, said conduit having a port for alternate flow from said valve casing to said chamber and from said chamber to said orifice, a valve member cooperable with said inlet, a float in said chamber and cooperable with said valve member to close said valve member upon predetermined liquid level in said chamber, a member having magnetic properties movable with said float, and magnetic means cooperable with said magnetic member and acting to hold said valve member closed until the liquid level drops sufficiently so that the float weight overcomes the force of said magnetic means.

13. Liquid fuel feeding means comprising a casing having a liquid fuel chamber, a tubular outlet member extending upward in said chamber and having an inlet below the chamber liquid level, a valve member longitudinally reciprocal in said outlet member and having a metering slot controlled by said outlet member, said valve member having a metering orifice within said outlet member, said outlet member having a side wall opening registering with said orifice when said slot is closed, valve means controlling admission of fuel under pressure to said chamber, a conduit having a port below the liquid level in said chamber, said conduit connecting the outlet of said valve means to said side wall opening, and means to open said valve means for a flow rate in excess of the flow rates of said port and said orifice.

14. Liquid fuel feeding means comprising a casing having a liquid fuel chamber, a tubular outlet member extending upward in said chamber and having an inlet below the chamber liquid level, a valve member longitudinally reciprocal in said outlet member and having a metering slot controlled by said outlet member, said valve member having a metering orifice within said outlet member, said outlet member having a side wall opening registering with said orifice when said slot is closed, valve means controlling admission of fuel under pressure to said chamber, a conduit having a port below the liquid level in said chamber, said conduit connecting the outlet of said valve means to said side wall opening, a float in said chamber and operatively connected to said valve means, and means cooperable with said float to cause intermittent opening of said valve means to a position for a flow rate in excess of the flow rates of said port and said orifice.

15. Liquid fuel feeding means comprising a casing having a liquid fuel chamber, a tubular outlet member extending upward in said chamber and having an inlet below the chamber liquid level, a valve member longitudinally reciprocal in said outlet member and having a metering slot controlled by said outlet member, said valve member having a metering orifice within said outlet member, said outlet member having a side wall opening registering with said orifice when said slot is closed, a sleeve valve slidable on said tubular valve member and operable to close said inlet, lost motion spring means interconnecting said sleeve valve and said tubular valve member and holding said sleeve valve in inlet closing position until movement of said tubular valve member closes said orifice, valve means controlling admission of fuel under pressure to said chamber, a conduit having a port below the liquid level in said chamber, said conduit connecting the outlet of said valve means to said side wall opening, and means to open said valve means for a flow rate in excess of the flow rates of said port and said orifice.

16. Fuel feeding means comprising a casing having a liquid fuel chamber and having a tubular outlet member having its inlet portion of enlarged diameter to provide an annular flow space and a cut-off shoulder, a valve member slidably fitting said outlet member below said shoulder and having a metering slot cooperate with said shoulder to regulate outlet flow from said chamber, the side wall of said outlet member having an aperture therethrough opening into said flow space on the inlet side of said shoulder, a valve casing having an inlet through the bottom wall of said chamber and having an outlet within said chamber, a tube connecting said outlet to said side wall aperture, a valve member in said casing and operable to shut said inlet and having a stem entering said chamber, a float in said chamber and connected to said stem, a member

having magnetic properties movable with said float, and magnetic means cooperable with said magnetic member to close said second-named valve member upon occurrence of predetermined liquid level in said chamber and to hold said second-named valve member closed until there is a predetermined decrease of liquid level.

17. Fuel feeding means comprising a casing having a liquid fuel chamber and having an outlet conduit with concentric valve seats and an enlarged diameter inlet portion providing an annular flow space and a cut-off shoulder, a cylindrical valve member reciprocally fitting said conduit and having a metering slot cooperable with said shoulder, said valve member having a valve portion engageable with the inner one of said seats after closure of said slot by said shoulder, a sleeve valve carried by said valve member and engageable with the outer one of said seats, said sleeve valve having a port for flow from and to said flow space when on its seat and having a lost-motion connection to said valve member, said conduit having a side wall aperture opening into said flow space, and a conduit for conveying liquid fuel under pressure from the exterior of said chamber directly to said aperture, said last-named conduit and said aperture having a capacity for flow to said space greater than the combined capacity of said port and said slot when said sleeve valve is seated.
